UNITED STATES PATENT OFFICE

99,014

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corporation of New Jersey

Application December 2, 1935, Serial No. 59,856

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in a plain base fabric, and series of parallel groups of two narrow closely adjacent threads or stripes running in straight relation through the entire fabric, and a single narrow

thread or stripe at each side of said series of groups separating one series from the adjacent series and running parallel to said groups, all of said threads or stripes being arranged in raised relation to said base fabric, said groups and said single stripe being spaced equal distances from one another, and short knobby ridges on said narrow threads or stripes, said ridges being intermittently spaced from one another on each thread or stripe and being in raised relation thereto.

I claim:

The ornamental design for a textile fabric or similar article of manufacture substantially as shown and described.

JOHN F. GAUL, JR.
